UNITED STATES PATENT OFFICE.

LEWIS FRITZ, OF CHICAGO, ILLINOIS.

ATTACHMENT FOR FOUNTAIN PENS AND THE LIKE.

Application filed December 5, 1921. Serial No. 519,897.

To all whom it may concern:

Be it known that I, LEWIS FRITZ, a citizen of the United States, and a resident of Chicago, in the county of Cook and State of Illinois, have invented a new and useful Improvement in Attachments for Fountain Pens and the like, of which the following is a full, clear, and exact description.

My invention relates to improvements in attachments for fountain pens and the like, and it consists in the combinations, constructions and arrangements herein described and claimed.

An object of my invention is to provide a device of the character described, which is thoroughly practical for the purpose intended and which is not likely to get out of order easily.

Other objects and advantages will appear in the following specification, and the novel features of the invention will be particularly pointed out in the appended claim.

My invention is illustrated in the accompanying drawings, forming part of this application, in which—

The figure is a sectional view of an embodiment of my invention.

In carrying out my invention, I make use of a fountain pen mechanism 1 and an automatic pencil mechanism 2 joined to one another, end to end.

My invention consists in a rubber collar 26 which provides means for holding the com-

bined fountain pen and automatic pencil in the coat or vest of the user and is adapted to be slipped over a connecting member 16 intermediate its length which in the present case serves as means for connecting the pen and pencil mechanism. The collar 26 is substantially T-shaped in cross section, as is shown in the drawing.

The collar 26 has substantially uniform plain cylindrical side walls 27 which are parallel with the bore 28 of the collar, which side walls engage with the fountain pen, pencil or the like. The T-shaped cross section of the collar is formed by the provision of rabbeted portions 29 concentric with and communicating with the bore at each end of the collar or ring, whereby the thickness of the collar or ring adjacent to its peripheral edge as shown at 30 is greater than that portion adjacent to the bore 28.

I claim:

In a device of the character described, having a barrel, a resilient ring adapted to be fitted concentric with said barrel, intermediate its length and to lie in close engagement therewith, said ring having uniform, plain cylindrical side walls, and having a rabbeted portion concentric with and communicating with the bore at each end of the ring, whereby the thickness of said ring adjacent its peripheral edge is greater than that portion adjacent to the bore.

LEWIS FRITZ.
